UNITED STATES PATENT OFFICE.

WILLIAM M. GROSVENOR, OF GRANTWOOD, NEW JERSEY.

DRYING AND TREATING FABRICS AND OTHER MATERIALS.

1,076,976.

Specification of Letters Patent.

Patented Oct. 28, 1913.

Application filed September 25, 1909. Serial No. 519,595.

To all whom it may concern:

Be it known that I, WILLIAM M. GROSVENOR, a citizen of the United States, and a resident of Grantwood, Bergen county, and 5 State of New Jersey, have invented certain new and useful Improvements in Drying and Treating Fabrics and other Materials, of which the following is a specification.

My invention relates to improvements in 10 drying and treating fabrics and other materials and is more especially designed with respect to improvements in drying and conditioning fabrics.

A general object of my invention is to 15 provide a method and arrangement whereby the drying and treating of such materials may be much more quickly, economically and efficiently carried out.

Many further objects, features and advantages will more clearly appear from the 20 detailed description given below, taken in connection with the accompanying drawings which form a part of this specification.

In the drawings, Figure 1 is a transverse 25 section of an apparatus arranged to carry out one form of my invention; Fig. 2 is a longitudinal vertical section of the left hand end of the apparatus shown in Fig. 1. Fig. 3 is a similar section of the right hand end 30 of the apparatus. Fig. 4 is a horizontal section taken on the line IV—IV of Figs. 2 and 3. Fig. 5 is a detail cross section showing the removable side panels and baffles of Fig. 1. Fig. 6 is a vertical section of the 35 parts shown in Fig. 5. Fig. 7 is a detail view, partly in section, of parts of the humidiifier. Fig. 8 is a detail view of part of one of the rolls and part of the adjustable side frame, showing some of the parts in a 40 modified form. Fig. 9 is a vertical transverse section of a modified form of apparatus, various heating means and rolls being removed, however, for the sake of clearness.

45 Referring to Fig. 1, 1 represents the floor upon which rests a suitable containing apparatus consisting of a bottom 2, sides 3, 3 and top 4. The containing apparatus is provided with ends 5, 5, preferably formed 50 of two sheets of glass, so that convenient inspection of various parts of the apparatus may be had therethrough. Within the apparatus there are stationary uprights 6, suitably spaced (see Figs. 4 and 5). These uprights are shown placed at the corners and one each in the middle on each side of the apparatus. The side pieces 3, 3 are made re-

movable by being secured to the uprights 6 by means of eye-bolts 7, secured in the uprights 6 and having wedges 8 passing through the eyes thereof, to firmly hold the side panels 3 in place.

60 Within the apparatus so far described I provide upright panels 9, consisting of two walls 10 and 11 having an air space therebetween to diminish the passage of heat therethrough. These panels 9 are also held in place and made removable by means of wedges 12, passing through suitable apertures in the uprights 6 (see also Fig. 6). The upright panels 9 extend vertically and are so arranged that spaces are provided at 65 each side of the apparatus, these spaces being bounded by panels 9, sides 3 and uprights 6, and being open at the top and bottom ends.

70 Between the two inner side panels 9 I provide stationary uprights 13, adjacent thereto, these uprights being connected by cross beams 14. Journaled in the uprights 13 at each end of the apparatus are rolls 15, there being about eight or nine of these shown 75 at each end of the apparatus. These rolls are provided so that their length may be adjustable. This is accomplished by having them made hollow and having their middle portions slotted, as clearly shown in the 80 lower part of Fig. 1, so that slits 16 are provided which interlock with one another, so that the ends of the rolls may be brought nearer together and yet the circumference of the rolls may be maintained substantially 85 the same (see also Fig. 8). In order to move the ends or hubs 17 of these rolls nearer together or farther apart, I provide adjustable frame pieces 18, provided with extensions 19, which engage a groove 90 20 in the hubs 17, so that when the side pieces 18 are moved the hubs necessarily move with them and the length of the rolls 15 is thereby adjusted. The side pieces 18 are moved and adjusted by means of screw 95 21, which may be operated in any suitable manner, as by hand or by gears 22 (shown in Fig. 1) driven by any suitable power.

100 Located near the bottom of the apparatus 105 is a suitable heating means 23, consisting of coils of pipes. These coils of pipes are located just below the lower roll 15. Located substantially opposite the third roll from the bottom is another set of heating means, 110 which may be designated as the main heating means 24. The heating means 24 also

consist of a plurality of pipes supplied by means of a pipe 25 fed from the main steam pipe 26. A valve 27 is interposed in order that the amount of steam and consequently the heat produced by the coils 24 may be suitably regulated. The exhaust from the coils 24 leads through pipe 28 through a suitable steam trap 29, so that the hot water thereby collected may be used to heat the coils 23 through the inlet pipe 30, the amount of flow being regulated by a valve 31 (see Fig. 1). Located opposite and just above each of the other rolls are separate sets of heating means 32, each consisting of coils of steam pipes fed from the main steam supply pipe 26 and controlled by valves 33. The exhaust from these various sets of coils leads to a main exhaust pipe 34.

Located near the top of the apparatus are two members 35, 35, each of which forms an extension for the interior side panels 9, and adjacent these side members 35 and between them and the side walls 3 are condensers 36, each condenser consisting of a series of cold water pipes supplied from inlet pipes 37 and provided with exhaust pipes 38. Below the condensing pipes is a trough 39, for the collection of moisture condensed by the coils 36 and from this trough are provided drip pipes 40. The whole of the condenser apparatus is supported on cross beams 41.

Within the lower part of the apparatus and secured to the uprights 13 I provide tanks 42, which form part of my humidifying apparatus. These tanks are provided with apertures 43 in their bottoms, through each of which is inserted a bunch of textile material which is held in place therein by means of pins 44 (see also Fig. 7), the textile material being denoted by 45. These tanks 42 extend substantially the whole length of the apparatus and are so arranged that the textile material 45 hangs below the lower end of the side panels 9 and into tanks 46. Warm water is supplied to the tanks 42 by supply pipes 47, which collect warm water condensed by one of the pipes in condensers 36. Any moisture dripping from the material 45 drops into the tanks 46, whence it is suitably carried away.

The fabric is carried into the apparatus through an aperture 48 in the front wall 5 of the machine by means of suitable chains 55 passing over rollers 49. The chains are designated by reference character 50 and are more clearly shown in Fig. 8. They consist of link members 51, provided with pins 52 suitably placed, over which pins the fabric is adapted to be caught. On the outside of the links 51 they are provided with lateral extensions 53, having rollers 54 on their ends which are adapted to work in the guides 55 secured to the movable side frame pieces 18. The chains 51 are guided and driven by

being passed over sprockets 56 secured to each hub of the rolls 15. There are two chains, one for each side of the machine, which as they pass up to the opening 48 may be somewhat spread apart in order to properly tenter the fabric. After passing through the aperture 48 they carry the fabric, which may be indicated by reference numeral 57, between two rolls 58 and 59. The roll 59 is placed within a tank 60 containing water, so that it will supply moisture to the fabric 57. Any excess of moisture supplied thereby is squeezed out by the roll 58. Thence the fabric is carried back and forth by the chains 50 and pins 51 over the various rolls 15 in between the various heating means 32, around and below the main heating means 24, until it passes just above the auxiliary heating means 23, whence the chain and fabric pass out of the apparatus, through the aperture 61 near the bottom of the machine and over the roll 62.

Suitable pieces of weather stripping 63 may be provided at the apertures 48 and 61, in order to prevent the outer air from getting into the apparatus (see Fig. 2). In a similar manner suitable weather stripping 64 may be provided at the edges of the panels 3 and 9 in order that the walls of the containing chamber may be substantially tight.

Located in between the various passes of fabric are baffles or baffle plates 65, hinged upon brackets 66 secured to the side panels 9. These features are more clearly shown in Figs. 5 and 6. The baffles 65 are provided with springy extensions 67, which lie against the sides of the panels 9, so that any material downward movement of the outer end of the baffles 65 is prevented. The baffles 65 are hinged by means of pivot pins 68 and are provided with an extension piece 69 which is arranged to contact with the brackets 66 in order to prevent the inner ends of the baffles 65 being given an excess upward movement. The sides and edges of the baffles are cut as shown in Fig. 5, being provided on one side with a slanting edge 70 and on the other edge with cutaway portions 71 and 72, the cutaway portion 71 being designed to permit the space for the stationary part 13 and the cutaway portion 72 being designed to provide space in which the frame piece 18 may laterally adjust itself.

The operation of the apparatus so far described is as follows: The fabric is placed upon the chains 50 by being caught over the pins 52 at its edges just before it passes into the apparatus. The chains are then slightly separated by suitable well known means in order to provide the proper tenter. The chains and fabric then pass over the roll 49 and into the apparatus through the opening 48. The fabric then passes between the rolls 58 and 59, which supply

moisture thereto or squeeze moisture therefrom according to the requirements of the fabric. Thence the fabric passes to the other end of the apparatus and back and forth over the various rolls 15 down to a point just above the main heating means 24, over the large roll 15' (Fig. 3) thence back and forth over the remaining rolls 15 to a point just above the heating means 23, whence it passes out of the apparatus through the opening 61 and over the roll 62. The sets of heating means 32 are arranged between the various passes of goods, above the main heating means 24.

15 The drying medium (and by this term I include the mixture of gases and water vapor contained in the apparatus) passes up through the central part of the apparatus and is brought up to the proper drying temperature by means of the heating means 24. It then comes in contact with the first pass of goods, whereby it is somewhat cooled by evaporation. It then comes in contact with the set of steam pipes just 20 above this pass of goods, so that its temperature is again raised to a sufficient degree to most efficiently dry the fabric. It then comes in contact with the next pass of goods, whereby it is again cooled by evaporation. This process continues until the 25 drying medium reaches the top parts of the goods, just entering the apparatus through the opening 48. In this way the material is subjected to a counter current of the drying medium and the temperature of the drying 30 medium is suitably supplied and regulated at different points in the apparatus, so that when the drying medium reaches the top of the apparatus it has absorbed a greater amount of moisture than would otherwise 35 be possible. Thus the temperature of the drying medium may be much greater when it comes in contact with the top parts of the goods than when it comes in contact with the bottom parts of the goods, that is, as the 40 drying medium rises, its temperature may be greatly increased so that it will absorb a passing above the top parts of the goods the passes above the top parts of the goods the 45 drying medium circulates over the members 35 and into the condensers 36, where the drying medium is thoroughly cooled and condensation produced therein in order to remove the moisture therefrom. The 50 drying medium then descends between the panels 9 and side walls 3 and passes among the material 45, whence a small amount of moisture is imparted thereto in order to render the medium sufficiently humid for 55 conditioning the fabric. If the medium is not sufficiently warm it may be slightly heated by means of preliminary heating coils 23, which are supplied with hot water from the exhaust of the main heating coils 60 24. If the drying medium is sufficiently

humid as it comes from the condensers, the humidifiers 42 and 45 may be omitted or their operation eliminated. From the heating means 23 the drying medium comes in contact with the various passes of goods just 65 above and properly condition the same before the material leaves the apparatus.

The various baffle plates are so arranged that the drying medium is caused to pass back and forth from side to side over the 70 various heating means and over the various passes of goods, so that the humid drying medium will come into thorough contact with all parts of the fabric.

In order to adjust the rolls to various 75 widths of goods, it is only necessary to rotate gears 22, whereby the side frames 18 are laterally adjusted, thereby moving the hubs 17 of the various rolls until they are suitably adjusted for the width of goods.

In order to provide warm water for the tanks 42 for the humidifying means, pipes 47 are provided, which receive condensed moisture from one or more of the pipes of the condensers 36. Easy access is had to the 80 condensers 36 for removal and repair by means of the upper removable panels 75, which are easily taken out by removing the upper wedges 8. In order to regulate the amount of flow of drying medium either 85 through one condenser or the other, an adjustable baffle 76 is provided, hinged to the right hand member 35 and maintained in its proper position by means of a cord 77 passing over a pulley 78 and having a weight 90 95 attached to its other end.

From the above it will be apparent that by my improvements I am enabled to carry out the conditioning process with the same medium which I use for drying, so that all 100 waste of energy which would otherwise be used for preparing a separate medium for these two purposes is eliminated, thus greatly reducing the cost of operation of the system. By providing the auxiliary 105 heating means 32 the drying medium is caused to take up a great deal more moisture than would otherwise be possible, so that the material is much more rapidly dried and the drying and condensation much 110 115 more economically effected.

By providing the apparatus with the removable panels 9, 9, and the removable sides 3 and 75, easy access is had to all parts of the apparatus for removal of the same and 120 for repair. Likewise, by constructing the baffles as shown they may be easily removed as follows: It is only necessary to remove the side panels 3 and 9 and the pivot pins 68, when the baffles may be rotated about 125 the part 69 as a center, so that they may be easily slid out of the apparatus. The slanting edge 70 permits of this pivotal movement without causing the removal of the baffles being obstructed in any way. The 130

adjustable upright members 18 are slightly cut away directly opposite the baffle plates 63, so that a comparatively small space is left through which the drying medium may escape between the baffles. The cut away parts 72 of the baffles permits of the movement of the members 18 laterally, so that they may be adjusted to various widths of goods.

Referring to Fig. 9, I there show a slightly modified form of apparatus, which however has the general structure of the apparatus already described. It has the same condensers 36 and the removable side walls 3 and 75 and the removable panels 9. It also has the same heating means 24 and adjustable baffles 76. Similar humidifying apparatus 42, 45, 46 and 47 is also provided. The various heating means 23 and 32 and the rolls 15 are omitted for the sake of clearness. In this modification, however, the side frames 13, 14 are spaced away from the side panels 9 to give a sufficient space therebetween to allow the entrance of a person, and the flooring 80 is provided on which he may walk. Suitable doors 81, one at each end of the apparatus, are provided for entrance thereto. The adjustable side frames 18 are moved by means of screw threaded rods 21 and gears 22 as in the first apparatus and these side frames carry the guides 55 for the chains which carry the fabric. Also in this figure I show a different arrangement of baffling means. This arrangement consists of pieces of flexible material 82, which extend substantially the whole length of the apparatus and which are secured along one of their sides to the guides 55 by means of screws 83 (see also Fig. 8). Two of these baffling means are arranged below the main heating means 24, as shown. The other side of these baffling means 82 passes over rolls 84 and has a weight 85 attached along the other edge. The weight 85 keeps the baffling material taut and since the baffling material is connected to the guides 55 and substantially to the edge of the fabric, the drying medium is caused to pass back and forth over the various passes of goods in its upward travel through the center of the apparatus. The baffles 82 may be easily removed by unscrewing the screws 83 and ready access is had to all parts of the apparatus without taking the side panels off, although these panels may be taken off when it is desired to replace large pieces of the apparatus.

By my improvements a great saving can be accomplished since the temperature of the air in the drying chamber may be maintained sufficiently high so that it may ultimately carry away the amount of water corresponding to the high percentage of saturation, and this may be done at or near the maximum temperature permissible with

the material being treated. Furthermore the size of the apparatus and the cost of installation is largely decreased because the amount of air or drying medium necessarily handled to remove a given tonnage of water is so greatly reduced. The alternately heating the drying medium and cooling the same by evaporation causes the drying medium to pass through epicycles of heating and evaporative cooling as it passes through its main cycle of humidifying, drying and conditioning. In this way a much higher temperature may be maintained at different points in the apparatus than would otherwise be permissible. This reinforcement of temperature may be carried out by different forms of apparatus without departing from the spirit and scope of my invention. By these improvements I avoid the great fall in temperature due to saturation of the air by a single passage of the material to be dried through the old forms of apparatus and at the same time avoid the access of cold air to the drying chamber.

The condensers are so designed that the flow of the cooling liquid therethrough is restrained, so that the cooling action is limited to that which is required to remove the necessary moisture and economically serve the heating chamber.

By providing the conditioning feature at a separate point in the same apparatus, the drying operation can be carried out entirely independent thereof and yet the two features are so closely connected that the same medium may be used for each with a much less expenditure of energy.

It will be understood that in my invention in one of its broader aspects moisture may be removed in any suitable manner from the drying medium as by absorption or by removing bodily a portion of the humid medium at one point and replacing it with dry air at another point of the closed circuit, as it is not necessary that a condenser be used for this purpose.

If desired the circulation of the drying medium may be increased in any suitable manner and with certain classes of goods it may be desirable to omit the top set of the heating means 32 in order that the first pass of goods shall not be greatly heated. The apparatus, however, can be operated with perfect safety, applying much greater heat to the upper passes of goods than can ordinarily be used without serious injury to the goods, as no cold dry air can strike the hot wet material.

One of the marked advantages of the apparatus is its long steady runs without the necessity of cleaning, no dust being carried into it from other parts of the mill and its own lint being largely caught by the condensers and washed away with the water. The goods are dried very much faster and the

labor in operating the machine is very much less and much more pleasant than in prior devices. Less time is required to dry a given quantity of goods since substantially all of the heat put into the apparatus is most effectively used and the goods being dried in the atmosphere which is saturated at the very beginning of the operation not only gradually becomes drier but also cooler as the goods descend and becomes nearly dried. The goods also has a finer "feel" and wears better.

It will be apparent that not only is the invention adapted to the treatment of the fabric itself but also to any form of material capable of being carried through the drier on the fabric as a carrier, or on a belt or similar conveyers, as it has already been practically applied to breakfast foods, hay, meat, fiber, etc.

Although I have described my invention with great detail, I do not desire to be limited hereto, since many modifications may be made without departing from the spirit and scope of my invention; but

Having fully and clearly described my improvements, what I claim as new and desire to secure by Letters Patent is:

1. An improved drying process which consists in subjecting the material to be dried to a current of drying medium in such a manner that such drying medium is repeatedly brought into contact and removed from contact with the material and when out of contact is heated to restore the temperature lost by evaporation, and then producing condensation in the drying medium and again passing it through repeated contacts and removals accompanied by heating as before, and continuing these cycles until the material is dried.

2. An improved drying process which consists in subjecting the material to be dried to a current of drying medium in such a manner that such drying medium is repeatedly brought into contact and removed from contact with the material and when out of contact is heated to restore heat lost by evaporation, and then removing moisture from the drying medium and again passing it through repeated contacts and removals accompanied by heating as before and continuing the cycles to sufficiently dry the material.

3. An improved drying process which consists in subjecting the material to be dried moving in one direction to a current of drying medium moving in a counter direction, in such a manner that such drying medium is repeatedly brought into contact and removed from contact with the material and when out of contact is heated to restore heat lost by evaporation, and then removing moisture from the drying medium and again passing it through repeated contacts and re-

movals accompanied by heating as before and continuing the cycles to sufficiently dry the material.

4. In an improved process for treating fabrics and other materials, circulating a suitable heated medium about the material to dry the same and then conditioning the material by subjecting the material to portions of the same medium while moist but under a condition of lesser humidity than it had on leaving the drying operation to condition the material.

5. In an improved process for treating fabrics and other materials, subjecting the material to a moist medium at a relatively high temperature, then subjecting the material to the medium at lesser temperatures and with lesser percentage of moisture, and then subjecting the material to the same medium after the medium has been cooled and a portion of its moisture removed to condition the material.

6. An improved drying and treating process which consists in subjecting the material to be dried to a current of drying medium whereby the medium absorbs moisture from the material and dries the same, and then subjecting the material to a medium containing moisture absorbed in said drying operation to humidify and cool the material.

7. In an improved process for treating fabrics and other materials, subjecting the material to be dried to a drying medium at a relatively high temperature, then subjecting the material to the same medium at a lower temperature, removing moisture from the same medium and then subjecting the material to the same medium to cause the medium to humidify and condition the material.

8. In an improved process for treating fabrics and other materials, subjecting the material moving in one direction to a drying medium moving in a counter direction, the material being first subjected to the medium at a relatively high temperature and humidity and then subjected to the medium at a lower temperature and humidity, cooling and removing moisture from the drying medium and then subjecting the material to the cooled medium to cause the medium to humidify and condition the material.

9. In an improved process for treating fabrics and other materials, subjecting the material moving in one direction to a drying medium in portions moving in a substantially closed circuit in a counter direction, so that each portion of the drying medium is intermittently subjected to the material, intermittently heating the drying medium between such subjection, then cooling the drying medium so as to produce condensation therein, and then subjecting the material to the cooled medium to cause

a conditioning or adjustment of moisture between the two, and to take up heat from the material to condition the material.

10. In an improved process for treating fabrics and similar materials, subjecting the material to a suitable medium circulating in a substantially closed circuit, drying the material in one part of said circuit and humidifying or conditioning the material in another part of said circuit. 70

11. In an improved process for treating fabrics and other materials, subjecting the material to a suitable drying medium to cause the medium to take up moisture from

15 the material to dry the material and then subjecting the material to the drying medium at a different temperature so that the medium will condition the material and then increasing the temperature of the medium so that it will again take more moisture. 80

12. In an improved process for treating fabrics and other materials, causing the material to move downwardly in layers, subjecting the layers to the action of ascending currents of a drying medium and regulating the temperature and humidity of the medium so that material is conditioned and the heat of the material is imparted to the medium during the lower part of the movement of the material and so that moisture is taken up by the medium from the material and heat imparted to the material during the upper part of the movement of the material. 85

13. In a drying system, means for subjecting the drying medium circulating in a circuit closed upon itself to a preliminary heating before it comes into proximity to the goods to be dried to dry the goods, and 100 means for alternately heating the drying medium and exposing the material to be dried thereto after said preliminary heating.

14. An improved drying apparatus having in combination suitable containing apparatus, means whereby the material is moved therethrough to be dried and means whereby a current of drying medium is caused to pass over the material and repeatedly brought into and removed from contact 110 with the material, means for heating the medium when out of contact with the material to produce a repetition of both heating and evaporative cooling and means whereby moisture is removed from the medium and part of the medium returned to again pass through said repetition of heating and evaporative cooling. 115

15. In a system for treating fabrics and other materials, suitable containing apparatus containing drying medium, means for moving the material through the apparatus, compression rollers for the material as it passes into the apparatus, means for heating the drying medium so that the material is subjected thereto at a relatively high tem- 120

perature and great humidity and then the material is subjected thereto at lesser temperatures and lesser humidities to dry the material, means for cooling the drying medium and removing a portion of the moisture therefrom after the drying operation, and means for causing the material to be subjected to the cool drying medium to condition the material. 75

16. In a system for drying and treating fabrics and other materials, suitable containing apparatus substantially closed to the outside atmosphere and arranged for a drying medium to circulate upwardly therein in one portion of the apparatus and downwardly therein in another portion of the apparatus, a condenser in said latter portion, means for moving the material downwardly in the former portion to dry the material, and means for causing the material to be subjected to the relatively cool drying medium after it leaves the condenser. 85

17. In an apparatus for treating fabrics and other materials, a chamber forming a circuit closed upon itself, means for causing the material to be treated to travel through said chamber, said chamber having a medium therein arranged to heat the material during a portion of its travel and means whereby the same medium will cool the material during another portion of its travel through said chamber. 95

18. In an apparatus for treating fabrics and other materials, a chamber substantially closed to the outside atmosphere, means in said chamber for drying the material and means in said chamber for conditioning the material after it has been dried. 100

19. In an apparatus for treating fabrics and other materials, a chamber forming a circuit closed upon itself, a heating means in said chamber for heating the drying medium and means for causing the material to be dried to pass below said heating means to condition the material. 110

20. In a drying system for treating fabrics and other materials, suitable containing apparatus, means for causing the material to travel through the apparatus, a medium for heating the material and absorbing moisture therefrom during part of its travel through the apparatus, means for condensing moisture from said medium absorbed during said heating, and means for returning a portion of said moisture to said material during another portion of its travel. 115

21. In an apparatus for treating fabrics and other materials, a chamber forming a circuit closed upon itself, means for removing moisture from said material in one portion of said chamber, means for moving the material to another portion of said chamber and means for conditioning the material in said last mentioned portion of said chamber. 125

with a portion of the moisture removed in the first mentioned portion of said chamber.

22. In an apparatus for the treatment of fabrics and similar materials, a chamber substantially closed to the outside atmosphere provided with inlet and outlet apertures for the material, means for dividing the chamber into two compartments communicating with one another at two points, means for moving the material to and fro within one compartment, means for drying the material in said compartment and means for conditioning the material in said compartment.

23. In an apparatus for the treatment of fabrics and similar materials, a chamber substantially closed to the outside atmosphere provided with inlet and outlet apertures for the material, means for dividing the chamber into two compartments communicating with one another at two points, means for moving the material to and fro within one compartment, means for maintaining different temperatures at different elevations in said compartment, and means for removing excess moisture from the apparatus.

24. In an apparatus for the treatment of fabrics and similar materials, a chamber substantially closed to the outside atmosphere provided with inlet and outlet apertures for the material, means for dividing the chamber into two compartments communicating with one another at two points, means for moving the material to and fro within one compartment, means for applying a regulated amount of heat at different elevations in said compartment, so arranged that at one point in said compartment the material will be cooled and a condenser in the other compartment provided with means for removing excess moisture from the apparatus.

25. In a drying apparatus, suitable containing apparatus, a plurality of layers of heating means therein, means for supporting the material to be dried therebetween so as to form alternate layers of heating means and of the material to be dried, and baffles arranged between various of the layers of heating means and material.

26. In a drying apparatus, means for moving the material to be dried therethrough in a plurality of passes, and separate heating means adjacent to various passes of the material, said apparatus being arranged to form a passage for causing a systematic circulation of a drying medium therein, and baffles arranged to cause the drying medium to pass alternately in opposite directions to and fro over various passes of the material.

27. In a drying apparatus, means for carrying the material to be dried therethrough, means for adjusting said carrying means to

varying widths of material, and baffling means arranged to cause the drying medium to effectively treat the material, said baffling means being adjustable for varying widths of material.

28. In a drying apparatus, means for separating the material to be dried into layers, a plurality of heating means between said layers and baffle plates extending below said heating means from opposite sides of the apparatus and extending substantially the length of the layers of the material taken parallel to the passage of the material.

29. In a drying apparatus, a plurality of heating means and baffle plates, a carrier arranged to carry the material to be dried back and forth therein between various of the heating means and baffle plates, and a condenser, said apparatus and baffle plates being so arranged that a passage is provided for directing a drying medium over the heating means, the material to be dried and the condenser.

30. In an apparatus for treating fabrics and other materials, suitable containing apparatus having a compartment for drying, a plurality of heating means in said compartment, means for moving the material back and forth over said heating means, a second heating means for heating the drying medium to the proper temperature for the drying operation, a condenser for cooling and producing condensation in the drying medium, and a third heating means for regulating the temperature of the medium from the condenser.

31. In an apparatus for treating fabrics and other materials, suitable containing apparatus arranged to form a passage for the circulation of the drying medium, means for heating the drying medium to bring it to the proper temperature for the drying operation, means for supporting the material to be dried and subjecting it to the drying medium, auxiliary heating means for adding heat to the medium at various stages of its passage about the material, a condenser for cooling and producing condensation in the drying medium after it leaves the material, means for adjusting the temperature and humidity of the drying medium after it leaves the condenser and means for subjecting the material to the drying medium after it leaves said adjusting means.

32. In an apparatus for treating fabrics and other materials, suitable containing apparatus arranged to form a passage for the circulation of the drying medium, means for heating the drying medium to bring it to the proper temperature for the drying operation, means for supporting the material to be dried and subjecting it to the drying medium, a condenser for cooling and producing condensation in the drying medium after it leaves the material, means for ad-

justing the temperature of the drying medium after it leaves the condenser, and means for subjecting the material to the drying medium after it leaves said adjusting means.

33. In an apparatus for treating fabrics and other materials, suitable containing apparatus arranged to form a passage for the circulation of the drying medium, means for heating the drying medium to bring it to the proper temperature for the drying operation, means for supporting the material to be dried and subjecting it to the drying medium, a condenser for cooling and producing condensation in the drying medium after it leaves the material, means for adjusting the humidity of the drying medium after it leaves the condenser, and means for subjecting the material to the drying medium after it leaves said adjusting means.

34. In an apparatus for treating fabrics and other materials, suitable containing apparatus arranged to form a passage for the circulation of the drying medium, means for heating the drying medium to bring it to the proper temperature for the drying operation, means for supporting the material to be dried and subjecting it to the drying medium, a condenser for cooling and producing condensation in the drying medium after it leaves the material, means for adjusting the humidity of the drying medium after it leaves the condenser, and means for subjecting the material to the drying medium after it leaves said adjusting means, said adjusting means including material impregnated with moisture in the passage for the drying medium and means for delivering moisture thereto from the condenser.

40 35. In an apparatus for treating fabrics and other materials arranged to form a passage for the circulation of the treating medium, a condenser, and material in said passage, said material being impregnated with moisture from said condenser.

36. In an apparatus for treating fabrics and other materials, suitable containing apparatus arranged to form a passage way through which the drying medium circulates, means for supporting material of varying widths to be dried, and baffling means arranged in operative relation thereto, said baffling means being adjustable to varying widths of material.

55 37. In an apparatus for treating fabrics and other materials, suitable containing apparatus arranged to form a passage way through which the drying medium circulates, means for supporting material of varying widths to be dried, baffling means arranged in operative relation thereto, said baffling means being adjustable to varying widths of material, and a plurality of sets

of heating means spaced among the material to be dried.

65 38. In an apparatus for treating fabrics and other materials, suitable containing apparatus arranged to form a passage way through which the drying medium circulates, means for supporting material of varying widths to be dried, baffling means arranged in operative relation thereto, said baffling means being adjustable to varying widths of material, and means for conditioning the material after it has been dried.

75 39. In a drier, the combination of adjustable width carriers for the material to be dried, and baffling means self-adjusting in accordance with the position of said carriers.

80 40. In an apparatus for drying and treating fabrics and other materials, suitable containing apparatus forming a closed circuit for the drying medium, a condenser in one portion of said circuit for cooling the drying medium, a humidifier in another portion of said circuit receiving its moisture from the condenser, a main heating means in another portion of the circuit for heating the drying medium suitably for the drying operation, an auxiliary heating means in the circuit between the humidifier and said main heating means for regulating the temperature of the humid drying medium, a plurality of sets of heating means in said circuit on the other side of said main heating means between said main heating means and the condenser, and means for moving the material among said sets of heating means so that the drying medium is alternately cooled by evaporation and heated by said sets, means for moving the material on the other side of said main heating means so that it is subjected to the humid drying medium from the humidifier, said means for moving the material being adjustable to varying widths of material, and flexible baffling means self-adjustable in accordance with the adjustment of said moving means.

85 41. The improved method of drying and conditioning fabrics and other materials, which consists in subjecting the material to be dried to a counter current of drying medium, causing the medium in a moist condition to act on the dried material to cool and condition the same, and then heating the same medium and causing it to dry the fresh material after the medium has performed the conditioning operation.

90 In testimony whereof, I have signed my name to this specification, in the presence of two subscribing witnesses.

WILLIAM M. GROSVENOR.

GORHAM CROSBY,
EDWIN SEGER.

Correction in Letters Patent No. 1,076,976.

It is hereby certified that in Letters Patent No. 1,076,976, granted October 28, 1913, upon the application of William M. Grosvenor, of Grantwood, New Jersey, for an improvement in "Drying and Treating Fabrics and Other Material," an error appears in the printed specification requiring correction as follows: Page 6, lines 43-44, for the word "havlug" read *having*; and that the said Letters Patent should be read with this correction therein that the same may conform to the record of the case in the Patent Office.

Signed and sealed this 18th day of November, A. D., 1913.

[SEAL.]

R. T. FRAZIER,

Acting Commissioner of Patents.
